CLAIM

The ornamental design for a consumer product package, as shown and described.

DESCRIPTION

FIG. 1 is a front perspective view of a consumer product package in an open position showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is rear perspective view thereof; and,

FIG. 9 is a front perspective view of the package in a closed position.

The broken lines shown in the drawings are for the purpose of illustrating parts of the article that form no part of the claimed design.

1 Claim, 7 Drawing Sheets
